UNITED STATES PATENT OFFICE.

EDWIN C. BELKNAP, OF CHICAGO, ILLINOIS.

LOCK.

1,102,207.

Specification of Letters Patent. Patented June 30, 1914.

Application filed October 18, 1912. Serial No. 726,586.

To all whom it may concern:

Be it known that I, EDWIN C. BELKNAP, a citizen of the United States, residing at Chicago, in the county of Cook and State 5 of Illinois, have invented certain new and useful Improvements in Locks, of which the following is a specification.

The present invention relates to a lock or catch adapted for use upon doors, windows, 10 screens and analogous devices, and relates particularly to that style or type of lock or catch known as the friction type.

The objects of the present invention are, to provide a device of the class specified 15 which is cheap and simple of construction and durable in usage, and which is so arranged as to permit of adjustment of the degree of tension exerted upon the catch member and to permit the catch member to 20 be adjusted in conformity to the shrinkage or swelling of the material surrounding the catch; and a further object of the invention is to provide means for readily inserting a tool to effect the adjusting operation. And 25 the invention further consists in the features of construction and combination of parts hereinafter described and claimed.

In the drawings, Figure 1 is a view showing a portion of a door or analogous device 30 and the casing therefor in section, and the catch of the present invention in operative position; Fig. 2 a longitudinal section of the catch of the present invention; Fig. 3 an end view, and Fig. 4 a detail showing the method 35 of applying the catch along the lower edge of the door or similar device.

Referring now to the drawings, and particularly to Figs. 1 and 2, the device as illustrated comprises a barrel or casing 5, which 40 is closed at its rear end 6 and open at the forward end 7. This casing or barrel is provided with an interiorly threaded surface 8, which receives a threaded surface 9 on the exterior of a sleeve 10, and said sleeve, 45 as better shown perhaps in Fig. 2, has its forward end 11 contracted. Arranged within the sleeve 10 is a catch member 12, which projects beyond the open forward end 11 of the sleeve 10 and is held in projected 50 position through the medium of a coil spring 13 located within the barrel or casing 5. This catch member 12 is designated to enter a recess 14 in a suitable striking plate 15, which is secured to the jamb of the door, 55 window or other article with which the

catch is employed, and the barrel or casing 5 is preferably provided with a series of ribs 16 which prevents the barrel or casing from turning within its seat during operation.

It is obvious that when the door, window 60 or other article is thrown or forced into closed position the catch member 12 will recede sufficiently during the closing operation to permit it to come into alinement with the opening in the striking plate 15, and 65 when such alinement has been reached the spring 13 will force the catch outward and into said opening, thereby holding the door, window or other article closed by a friction locking means. 70

As heretofore stated, the sleeve 10 and the barrel 5 are provided with exterior and interior threaded surfaces respectively. By the provision of these elements the sleeve 10 can be advanced or receded within the barrel 75 5 as desired. This advancement or recession of the sleeve 10 will obviously move the catch 12 inward or outward with respect to the forward, open end 7 of the casing 5, and will increase or decrease the spring tension 80 upon said catch, owing to the fact that as the catch member is moved in or out it will compress or release the spring 13 in accordance therewith. Thus an arrangement is provided which permits of an adjustment of 85 the tension upon the catch member in conformity to the usage to which the device is put and the necessities thereof, or the adjustment can be made in order to maintain a proper correlation between the striking 90 plate and catch in conformity to the spacing of the door, window or other article from its jamb, and in conformity to the swelling or shrinking of the woodwork composing said door, window or other article or jamb there- 95 for.

In order to readily permit the advancement or retraction of the sleeve 10 within the barrel 5, I show in the construction illustrated companion notches or recesses 17, of 100 a nature to accommodate a suitable spanner wrench, and by means of the insertion of this simple tool in position the sleeve can be readily rotated to move it in or out of the barrel as desired. 105

In the form illustrated in Fig. 4, suitable leaves or lugs 18 are provided for the purpose of fastening the barrel onto the lower end of a door or similar device. In this construction the latch member engages with a 110

suitable detent attached to the wall or other portion of the structure against which the door or similar device swings when open.

It will be noted that however the sleeve 10 is adjusted the latch member 12 will always project the same distance beyond the open end 11 of said sleeve and hence there will be no difference in the locking efficiency of the catch, no matter what the adjustment 10 may be.

I claim:

In a device of the class described, the combination of a latch member, retaining means therefor consisting solely of an outer section 15 and an inner section, said outer section comprising a cup-shaped casing provided with an interiorly threaded surface and an outer marginal flange adapted to afford an abutment for properly positioning the casing in place, said inner section consisting of an open ended sleeve provided with an exteriorly threaded surface meshing with the interiorly threaded surface of the casing,

and having its outer end contracted to provide a rim formed to furnish an engaging 25 surface for the application of an adjusting tool, a catch member slidable within said sleeve and projecting outwardly therefrom and held against complete withdrawal by a spring within the casing for projecting the catch member outwardly from the sleeve, said inner section, when turned, moving in or out from the outer section, varying the 35 degree of projection of the catch member with respect to the outer face of the structure to which the lock is attached, and simultaneously varying the degree of the tension of the spring, whereby said tension is increased as the catch member is moved inward and decreased as said member is moved outward, substantially as described.

EDWIN C. BELKNAP.
